ABSTRACT OF THE DISCLOSURE

An adjustable tail pipe for well tools telescopically adjustable from a first position, at which it projects from a tool body to a second position at which it projects further from the tool and is locked in the second position by mechanically engaged lock elements.

The present invention relates to a tail pipe lock for well tools, and more particularly to a telescopic tail pipe assembly which is adapted to be landed at the bottom of a well such as an oil or gas well, or the like drilled hole, or landed on some other abutment placed in the well, and when landed to cause operation of a well tool thereabove in a running in string of pipe, such as drill pipe or other tubing or well pipe.

This invention is an improvement in the adjustable tail pipe for well tools disclosed in the pending application for United States Patent, Serial No. 618,910 filed in the name of Theodore A. Raugust on Feb. 27, 1967.

In the making of drill stem tests of wells during the drilling operation, a testing apparatus is run into the well on drill pipe, such testing apparatus including means for taking a sample of the fluids in the earth formation about the well bore and between a pair of axially spaced packers which are adapted to be set in the open well bore or open hole so as to straddle the earth formation from which it is desired that the sample be taken, and the packers being separated by a perforated or slotted pipe section into which the formation fluid is to pass. In some instances the effective bottom of the well is not in a location relative to the zone or formation to be tested as to enable proper setting of the straddle packers by setting a tail pipe down on the bottom of the well. Heretofore, if an improper seal was made by the packers, for example due to the fact that the packers are too low relative to the zone to be straddled, it has been necessary to pull the entire length of drill pipe to change the effective distance between the bottom of tail pipe and the straddle packer. Such an operation is costly and time consuming.

The adjustable tail pipe of the aforementioned pending application provides hydraulic lock means in an extensible tail pipe adapted to operate a well tool, and which is adjustable in length between first and second lengths.

More specifically, an object of the invention is to provide an adjustable tail pipe construction in which an adjustment of the effective length of the tail pipe is made by simple manipulation of the pipe string in which the well tool and tail pipe are installed and in which a positive lock is provided to hold the tail pipe in its extended condition.

In accomplishing the foregoing, it is another object of the invention to provide an adjustable tail pipe construction and lock means for holding the same in a position of adjusted length without regard to the depth of the well bore and the hydrostatic pressure of fluid in the well bore.

Another object is to provide the combination of a well tool adapted to be operated in response to the setting down of the weight of the running in string of pipe, and an adjustable tail pipe and positive lock means also operated

2

in response to the setting down of the weight of the running in string of pipe to cause operation of the well tool at an adjusted elevation in the well bore. More specifically, such combination includes a straddle packer of a drill stem tester.

- 5 Other objects and advantages of the invention will be hereinafter described or will become apparent to those skilled in the art and the novel features of the invention will be defined in the appended claims.
- 10 In one of its aspects, the invention briefly is embodied in an adjustable tail pipe for operating a well tool upon engagement of the tail pipe with the bottom of a well, including telescopic upper and lower sections, releasable means interconnecting the sections together in a first relative position and releasable responsive to the application of a force tending to telescopically shift the sections from the first position to a contracted position, and means including coengagable lock elements on one of the sections for positively interconnecting the telescopic sections in a second relative position following telescopic shifting of the sections to an extended position, wherein the last-mentioned means include opposing shoulders axially spaced on the telescopic sections, and the lock elements include expansible wedge members and means for expanding the 15 expansive wedge members, the expansible wedge members being engageable with one of the opposing shoulders and the means for expanding the same being engageable with the other of the opposing shoulders, and means for effecting fluid pressure responsive expansion of the wedge members into engagement with the other of the opposing shoulders.

In another of its aspects the invention briefly includes an adjustable tail pipe for operating a well tool upon engagement of the tail pipe with the bottom of a well, the tail pipe including an upper tubular body adapted for connection beneath a well tool, a lower tubular body including a rod telescopically extending into the upper body, means for releasably interconnecting the bodies in relative positions with the rod extended fully into the 20 upper body, an upwardly facing shoulder adjacent the upper end of the rod, a downwardly facing shoulder in and adjacent the lower end of the upper body, lock means on the rod above the upwardly facing shoulder, means for limiting telescopic extension of the rod from the upper body to a relative position of the upper body and lower body at which the downwardly facing shoulder is above the lock means following release of the interconnecting means, and means for expanding the lock means for engagement with the downwardly facing shoulder and 25 engagement with the upwardly facing shoulder to maintain the rod in the extended position.

In the drawings:

FIG. 1 is a view generally showing in elevation a drill stem testing tool including a straddle packer set in a well bore in a first, ineffective position, with the adjustable tail pipe of the invention landed at the bottom of the well;

FIG. 2 is a view generally corresponding to FIG. 1, but showing the tester tool and straddle packer set in a second, effective position in the well bore, with the tail pipe adjusted, locked in a position of extended length, and landed at the bottom of the well;

FIG. 3a is an enlarged view in vertical section showing the upper portion of the adjustable tail pipe and lock in condition for running into the well bore;

FIG. 3b is a downward extension of FIG. 3a;

FIG. 4 is a transverse sectional view as taken on the line 4—4 of FIG. 3a;

FIG. 5a is a fragmentary view in side elevation of the portion of FIG. 3b embraced by the line 5a—5a, showing the frangible retaining ring for releasably holding the tail pipe in the position of FIG. 1;

FIG. 5b is a view corresponding to FIG. 5a, but showing the retaining ring sheared in response to downward force applied by the running in string;

FIG. 6 is a view in longitudinal section showing the tail pipe assembly, with central portions broken out, filling with fluid as the tail pipe is being stretched out and the running in string is elevated after shearing of the retaining ring as seen in FIG. 5b;

FIG. 7a is a fragmentary view in longitudinal section showing the tail pipe lock stretched out and under tension responsive to upward movement of the running in string;

FIG. 7b is a view corresponding to FIG. 7a, but showing the lock elements pressure loaded to the locking position during downward movement of the upper tail pipe section relative to the lower tail pipe section; and

FIG. 7c is a view corresponding to FIGS. 7a and 7b, but showing the upper tail pipe section locked against further downward movement relative to the lower tail pipe section.

Like reference characters in the several views of the drawings and in the following description designate corresponding parts.

Referring to FIG. 1, there is illustrated a well tool assembly embodying the present invention, such assembly including a hydraulic main valve of conventional construction and forming part of a drill stem tester adapted to be mounted in a running in string of pipe, the tester also including a straddle packer assembly consisting of an upper packer and a lower packer adapted to engage the well bore wall and form spaced seals isolating an intermediate length of perforated pipe into which a sample of formation fluid is to be taken. The packers are typically set, or caused to be deformed and moved outwardly into sealing engagement with the well wall in response to the setting down of weight on a tail pipe which depends from the straddle packer assembly, all as is well known in the art.

However, as shown in FIG. 1 the potentially productive earth formation to be tested may consist of narrow sand strata, one of which is designated F. Thus, if the packers do not properly isolate the formation F and one of the packers is disposed in the sandy formation F, an ineffective seal and an ineffective test may result. It is not uncommon in certain oil and gas producing areas that the upper packer may be disposed in an improper location as illustrated in FIG. 1 and the pipe string must be pulled from the well to change the length of the tail pipe so that upon re-running the string of pipe and the new tail pipe, the packers will be properly set as shown in FIG. 2. Such round tripping of the running in string to modify the tool is time consuming and costly. Many such problems may be avoided by adjustment of the effective length of the tail pipe, and in FIG. 2 the adjustable tail pipe has been extended to raise the location of the packers in the well bore so that they properly isolate the formation F and are engaged with the well wall at locations where better sealing is possible.

The adjustable tail pipe comprises an upper tubular section 1 and a lower tubular section 2 telescopically engaged and interconnected at 3 by frangible means which will be more fully described and which maintains the first effective tail pipe length as shown in FIG. 1 until broken to allow the tail pipe to telescope to the second effective length shown in FIG. 2.

Referring to FIGS. 3a through 5b, the structure of the adjustable tail pipe will be described in detail. As seen in FIG. 3a, the tubular body 1 is connected as at 4 to a head 5 which is adapted to be connected as by a pin and box threaded joint 6 to the lower end of the straddle packer assembly. The head 5 has a wall 7 closing the upper end of body 1 and separating the interior of body 1 from the interior of the packer assembly. At its lower end the upper body 1 has a pair of downwardly extended connector fingers 8, 8 forming a part of the

frangible connection 3, whereby the lower body 2 is connected to the upper body 1, as seen in FIGS. 3b and 5a.

The upper end of body 2 is axially slotted at 9, 9 to receive fingers 8, 8 and in addition is circumferentially slotted at 10 to receive arcuate retaining ring segments 11 and 12, these segments 11 and 12 also extend arcuately through slots 13 in fingers 8, 8 so as to interlock the fingers with the body section 2. Ring segments 11 and 12 are held in slots 10 and 13 by a wire or band 14, and thus the body sections 1 and 2 are held in a first axial relationship. Clearance space 15 is provided between the upper end of body 2 and the lower end of body 1, as well as between the bottom of fingers 8, 8 and the bottom of slots 9. The ring segments are composed of such material, aluminum for example, as will be shearable by the side walls of fingers 8, 8 and slots 9 when sufficient downward force is applied to the upper body 1 and the lower body 2 is landed on the bottom of the well. FIG. 5b illustrates the sheared ring segment 12, and thereafter, the body sections 1 and 2 are movable to a second axial relationship, as will hereinafter be described.

Referring again to FIGS. 3a and 3b, the tail pipe assembly includes an inner tubular member or connecting rod 16 formed as part of or connected to the body 2 as at 17 and extended upwardly within the body 1 so as to be telescopically adjusted relative to the body 1 upon release of the retaining means 3. At the upper end of connecting rod 16 is lock means generally indicated at 18.

This lock means includes a support 19 in the form of a tubular extension of the connecting rod 16 formed on or connected to the latter as at 20. On the support 19 is a lower shoulder or upwardly facing abutment 21 and at the upper end of the support 19 is a nut providing a downwardly facing abutment 22. Lock means 18, therefore, is mounted on the support 19 between the upwardly and downwardly facing abutments 21 and 22.

More specifically, the lock means 18 comprises an annular divider piston 23 which sealingly engages the inside wall of body 1 and the support 19, the piston separating the space between support 19 and body 1 into an upper chamber 24 and a lower annular chamber 25 defined between connecting rod 16 and the body 1.

Passage means are provided for balancing the pressure in the chambers 24 and 25. Such passage means includes a passage 26 extending through the connecting rod 16 and including a passage 26a in the support 19. At its lower end, passage 26 leads to a passage 26b in a bull nose 27, at the lower end of the body 1, the passage 26b typically communicating with the well bore. In passage 26 is a check valve including a seat 28 circumscribing the passage and engageable by a downwardly seating ball valve 29. Thus when pressure inside chamber 24 is less than pressure of fluid in the well the valve will open to fill the chamber 24 with fluid at the same pressure as well pressure.

In addition, body 1 is formed with a passage 30 (see FIG. 3b) included in the pressure balancing passage means which leads between the chamber 25 and the well bore outside the body 1. Communication between chambers 24 and 25 is established through a number of restricted passages 31 for a purpose which will hereinafter more fully appear, but it will now be apparent that pressure will be normally balanced across piston member 23, but under some circumstances, as will be later described, balance is retarded by the restriction to flow through restricted passage 31.

The lock means 18 includes also laterally outwardly shiftable lock elements in the form of wedge members 32 arranged at angularly spaced locations about piston 23. Each wedge member is provided with a T-head 33 shiftable mounted in a T-slot 34 in the lower portion of piston 23. These wedge elements 32 are held retracted as shown in FIG. 3a by means of a resilient band 35 which encircles the wedge elements. Beneath the wedge elements 32 is an expander 36 slidably disposed on the support 19 and

engageable with abutment 21. The expander 36 has a conical end engageable with the lower ends of the lock elements so that upon axial movement of the expander and elements toward one another the elements will be expanded laterally outwardly, but upon opposite movement of the expander and the elements the latter will move inwardly.

In the normal or running in condition shown in FIGS. 3a and 3b, it will be noted that the expander 36 is seated against the shoulder 21 and that the lock elements 32 are retracted. Under these conditions the body 1 and body 2 are maintained in their first relative position of composite length by the shearable retaining ring segments 11 and 12. During running of the string into the well bore, the tail pipe may fill with fluid through the check valve 29 and the passage 30 in the body 1.

When the tail pipe reaches the bottom of the well, as shown in FIG. 1, the weight of the running in string of pipe will shear the ring segments 11 and 12 and thereafter the weight of the running in string will cause expansion of the packers into engagement with the well wall. If it appears that the packers are not properly positioned to provide a good seal with the formation then, as will now be described, the effective length of the tail pipe may be extended.

In FIG. 6 is illustrated the next manipulative step, whereby the tail pipe is extended in length, and is filled with fluid as its internal volume expands. This step involves lifting up on the running in string, during which body 2 will remain at or adjacent the bottom of the hole and the upper body 1 will move upwardly telescoping with respect to the rod 16 until such telescoping is arrested and the tail pipe assembly is supported in tension as shown in FIG. 7a. During telescopic extension of the tail pipe, an intermediate state of which is shown in FIG. 6, the check valve 29 will open to allow entry of fluid into the expanding space within the tail pipe, and fluid may also enter port 30 in body 1.

Referring more specifically to FIG. 7a, it will be noted that when the tail pipe is supported in tension, the upper body 1 has telescoped upward relative to the lower body 2 causing an internal abutment means on shoulder 40 of the body 1 to engage the lower end of expander 36, moving the latter upwardly off of shoulder 21. The lock elements 32 are cammed outwardly and the T-heads 33 engage at their upper ends with the piston 23 which, in turn, abuts with the upper abutment means 22. Thus the lower section of the tail pipe, including body 2 and rod 16, is suspended from the upper section of the tail pipe.

In the next phase of manipulation of the running in string, as shown in FIGURE 7b, the assembly is again lowered to cause the lower section of the tail pipe to land at the bottom of the well, which will arrest further downward movement of the tail pipe assembly as a unit, but the upper section will continue to move downwardly, telescoping over the rod 16, thereby reducing the internal volume of fluid within the assembly. The end wall 7, at the top of body 1, displaces fluid from chamber 24 into chamber 25 through restricted passages 31 in the barrier piston 23, while check valve 29 closes to prevent flow from chamber 24 through the passageways 26a in support 19 and 26 in connecting rod 16. Inasmuch as the chamber 25 opens to the exterior of the tail pipe assembly through the port 30, the fluid displaced from chamber 24 into chamber 25 provides a differential pressure across the barrier piston 23 acting downwardly on the latter and forcing it downwardly, thereby causing a laterally outward force to be imposed on the lock elements 32 by expander 36, which in turn is forced downwardly against the downwardly moving abutment 40 of upper body 1. As such downward movement continues, the expander 36 will again engage the abutment 21 on stationary body 19 arresting downward movement of expander 36 while the differential pressure across barrier piston 23 continues

to maintain the lock elements 32 in the expanded condition.

In the final stage of operation, as seen in FIG. 7c, it will be noted that the upper ends of the expanded lock elements engage a downwardly facing abutment 41 within upper body 1 so that the weight of the running in string will be transmitted from abutment 41 to the lock elements 32 and through them to expander 36 which is abuttingly engaged with upwardly facing abutment 21. At this time, of course, the tail pipe assembly is adjusted to its second or extended condition having an effective length in excess of its above-described first position a distance substantially equal to the length of the connecting rod. Various rod lengths may be employed, say on the order of five feet, so as to enable setting of the packers at a five foot higher elevation in FIG. 2 than in FIG. 1.

Inasmuch as the forces imposed on the tail pipe assembly and the locking means 18 as they are being operated are substantial, the restricted passageways 31 through the barrier piston 23 are preferably such as to cause a dash-potting of the downward movement of the upper body 1 through the stages shown in FIGS. 7b and 7c, so as to relieve the lock means of heavy shock loads.

While the specific details of the invention have been herein shown and described, changes and alterations may be made without departing from the spirit of the invention as defined in the appended claims.

I claim:

1. An adjustable tail pipe for operating a well tool upon engagement of said tail pipe with the bottom of a well, comprising telescopic upper and lower sections, releasable means interconnecting said sections together in a first relative position and releasable responsive to the application of a force tending to telescopically shift said sections from said first position to a contracted position, and means including coengageable lock elements on one of said sections for positively interconnecting said telescopic sections in a second relative position following telescopic shifting of said sections to an extended position, wherein said last-mentioned means include opposing shoulders axially spaced on said telescopic sections, and said lock elements include expansible wedge members and means for expanding said expansible wedge members, said expansible wedge members being engageable with one of said opposing shoulders and said means for expanding the same being engageable with the other of said opposing shoulders, and means for effecting fluid pressure responsive expansion of said wedge members into engagement with said other of said opposing shoulders.

2. An adjustable tail pipe for operating a well tool upon engagement of said tail pipe with the bottom of a well, comprising telescopic upper and lower sections, releasable means interconnecting said sections together in a first relative position and releasable responsive to the application of a force tending to telescopically shift said sections from said first position, and means including coengageable lock elements on said sections for positively interconnecting said telescopic sections in a second relative position following telescopic shifting of said sections, one of said telescopic sections including a connecting rod telescopically extending into the other section, said means for interconnecting said sections in said second position including a support at the inner end of said rod, laterally movable lock elements on said support, axially opposing shoulders on said support and said other section, and means for laterally moving said lock elements from a retracted position to a laterally shifted position between said shoulders to hold said sections in said second position, wherein the means for laterally moving said lock elements includes an expander and means for effecting engagement of said lock elements with said expander including a fluid pressure operated piston, said lock elements being carried by said piston, said one of said sections having a chamber in which said piston is disposed, and said sections having passage means for admitting fluid

to said chamber and discharging fluid from said chamber.

3. An adjustable tail pipe for operating a well tool upon engagement of said tail pipe with the bottom of a well, comprising telescopic upper and lower sections, releasable means interconnecting said sections together in a first relative position and releasable responsive to the application of a force tending to telescopically shift said sections from said first position, and means including coengageable lock elements on said sections for positively interconnecting said telescopic sections in a second relative position following telescopic shifting of said sections, one of said telescopic sections including a connecting rod telescopically extending into the other section, said means for interconnecting said sections in said second position including a support at the inner end of said rod, laterally movable lock elements on said support, axially opposing shoulders on said support and said other section, and means for laterally moving said lock elements from a retracted position to a laterally shifted position between said shoulders to hold said sections in said second position, wherein the means for laterally moving said lock elements includes an expander and means for effecting engagement of said lock elements with said expander including a fluid pressure operated piston, said lock elements being carried by said piston, said one of said sections having a chamber in which said piston is disposed, and said sections having passage means for admitting fluid to said chamber and discharging fluid from said chamber including a passage leading into said chamber through said rod, and check valve means for closing said passage upon expansion of said lock elements by said piston.

4. An adjustable tail pipe for operating a well tool upon engagement of said tail pipe with the bottom of a well, comprising telescopic upper and lower sections, releasable means interconnecting said sections together in a first relative position and releasable responsive to the application of a force tending to telescopically shift said sections from said first position, and means including coengageable lock elements on said sections for positively interconnecting said telescopic sections in a second relative position following telescopic shifting of said sections, one of said telescopic sections including a connecting rod telescopically extending into the other section, said means for interconnecting said sections in said second position including a support at the inner end of said rod, laterally movable lock elements on said support, axially opposing shoulders on said support and said other section, and means for laterally moving said lock elements from a retracted position to a laterally shifted position between said shoulders to hold said sections in said second position, wherein the means for laterally moving said lock elements includes an expander and means for effecting engagement of said lock elements with said expander including a fluid pressure operated piston, said lock elements being carried by said piston, said one of said sections having a chamber in which said piston is disposed, and said sections having passage means for admitting fluid to said chamber and discharging fluid from said chamber including a passage leading into said chamber through said rod, check valve means for closing said passage upon expansion of said lock elements by said piston, and an-

other chamber on the other side of said piston from the first-mentioned chamber, said piston having passages communicating with said both of said chambers.

5. An adjustable tail pipe for operating a well tool upon engagement of said tail pipe with the bottom of a well, comprising an upper tubular body adapted for connection beneath a well tool, a lower tubular body including a rod telescopically extending into said upper body, means for releasably interconnecting said bodies in relative positions with said rod extended fully into said upper body, an upwardly facing shoulder adjacent the upper end of said rod, a downwardly facing shoulder in and adjacent the lower end of said upper body, lock means on said rod above said upwardly facing shoulder, means for limiting telescopic extension of said rod from said upper body to a relative position of said upper body and lower body at which said downwardly facing shoulder is above said lock means following release of said interconnecting means, and means for expanding said lock means for engagement with said downwardly facing shoulder and engagement with said upwardly facing shoulder to maintain said rod in said extended position.

6. An adjustable tail pipe as defined in claim 5, wherein the means for expanding said lock means includes a piston disposed about said rod, said lock means including expandable lock elements carried by said piston and engageable by said downwardly facing shoulder, said lower body having a passage leading therethrough and having a downwardly seating check valve therein, said upper member having a top closure forming with said barrier piston a pressure chamber into which said rod extends.

7. An adjustable tail pipe as defined in claim 6 wherein said piston is provided with restricted passages therethrough for dashpotting engagement of said downwardly facing shoulder with said lock elements.

8. An adjustable tail pipe as defined in claim 6, wherein said piston is provided with restricted passages therethrough for dashpotting engagement of said downwardly facing shoulder with said lock elements, said rod below said piston and said upper body forming a sectional chamber into which said restricted passages extend, and said upper body having a port leading to the exterior thereof from said second chamber.
